UNITED STATES PATENT OFFICE

2,007,900

MINING APPARATUS

Charles F. Osgood, Claremont, N. H., assignor to
Sullivan Machinery Company, a corporation of
Massachusetts

Application March 1, 1930, Serial No. 432,541

19 Claims. (Cl. 262—28)

This invention relates to mining apparatus and more particularly has reference to improvements in coal mining apparatus of the wheel mounted "universal" type adapted to operate while supported and guided by a mine trackway.

An object of this invention is to provide an improved coal mining apparatus. Another object is to provide an improved coal mining apparatus of the wheel mounted "universal" type having improved adjustable kerf cutting mechanism operative to cut kerfs in parallel planes either horizontally or vertically. Another object is to provide an improved coal mining apparatus of the wheel mounted type adapted to operate while supported and guided by a mine trackway and having improved adjustable kerf cutting mechanism whereby a kerf may be cut at or near the level of the mine bottom outside and below the level of the mine trackway. Still another object is to provide in a mining apparatus of the aforesaid character improved adjustable kerf cutting mechanism whereby the cutter bar may be positioned to cut a horizontal kerf at or near the level of the mine bottom outside the mine trackway or to cut a vertical kerf. Yet another object is to provide in a mining apparatus of the aforesaid character improved adjustable kerf cutting mechanism whereby the cutter bar may be positioned to cut a horizontal kerf at or near the level of the mine bottom or at or near the level of the mine roof, thereby enabling the apparatus to operate either as a mounted bottom cutter or a top cutter to suit varying mining conditions. Still another object is to provide an improved top cutter mining apparatus wherein a plurality of adjusting mechanisms for the cutter mechanism is provided for adjusting the cutting device. A further object is to provide an improved mechanism for adjusting the cutting mechanism into different elevated and angular positions relative to the truck and driven from the same motor as that which drives the truck wheels to propel the apparatus along the mine trackway. Another object is to provide an improved coal mining apparatus of the wheel mounted type adapted to operate while supported and guided by a mine trackway having supports extremely flexible in adjustment whereby the cutting device may be positioned at or near the level of the mine bottom outside the mine trackway, at or near the level of the mine roof, or may be adjusted into positions to make vertical or shear cuts, it also being possible to tilt the cutting mechanism about a transverse axis to vary the angle of the cutting device relative to the horizontal. Yet another object

is to provide an improved coal mining apparatus of the wheel mounted track supported and guided type having improved motor driven devices for swinging the kerf cutting mechanism relative to the truck, for adjusting the cutting mechanism into different elevated positions relative to the truck and for tilting the cutting mechanism, for rotating the cutter head, for adjusting the cutting device bodily toward and from the head axis, and for swinging the cutting device about its pivot. These and other objects of this invention will, however, hereinafter more fully appear in the course of the following description and as more particularly pointed out in the appended claims.

In the accompanying drawings there is shown for purposes of illustration one form which the invention may assume in practice.

In these drawings,—

Fig. 1 is a plan view of the illustrative embodiment of the improved mining apparatus.

Fig. 2 is a side elevational view of the mining apparatus shown in Fig. 1.

Fig. 3 is an enlarged fragmentary plan view of the apparatus shown in Fig. 1 with parts shown in horizontal section to illustrate structural details.

Fig. 4 is a central longitudinally extending vertical sectional view taken substantially on line 4—4 of Fig. 3.

Fig. 5 is a central longitudinally extending vertical sectional view taken substantially on line 5—5 of Fig. 1.

Fig. 6 is a transverse vertical sectional view taken substantially on line 6—6 of Fig. 4.

Fig. 7 is a detail sectional view taken substantially on line 7—7 of Fig. 3.

Fig. 8 is a horizontal section on a plane corresponding to the line 8—8 of Fig. 5.

Fig. 9 is a transverse vertical sectional view taken substantially on line 9—9 of Fig. 1.

Fig. 10 is a horizontal sectional view illustrating details of the mechanism shown in Fig. 9.

Fig. 11 is a diagrammatic side elevational view illustrating the mining apparatus in a mine with the cutting device operating at the level of the mine bottom.

Fig. 12 is a diagrammatic plan view illustrating the apparatus making an arcwall cut at or near the level of the mine bottom.

illustrating the apparatus operating as a shear or vertical cutter.

In this illustrative embodiment of the invention there is shown a coal mining apparatus of 5 the wheel mounted track supported and guided type generally comprising a self-propelled truck 1 mounted on wheels 2 adapted to travel along a mine trackway 3. Mounted on the truck for adjustment vertically relative thereto is a horizontal turntable 4 which in turn has supported 10 thereon for horizontal swinging movement therewith relative to the truck, a frame 5. Supported on the forward end of the frame 5 for rotation about a longitudinal axis is a cutter head 6 having adjustably mounted thereon a cutter bar 7. Suitable motor operated devices 15 are provided for driving the truck wheels, for adjusting the turntable 4 relative to the truck, for swinging the frame 5 relative to the truck, for 20 rotating the cutter head 6 about its axis, and for adjusting the cutter bar 7 relative to the cutter head as will hereinafter be described:

Suitable mechanism is provided to propel the truck in either direction at a transport or at a 25 cutting speed. Carried on the rear end of the truck frame is a motor 10 which may be of the reversible electric type having its armature shaft 11 connected by a coupling 12 to a longitudinally extending shaft 13 (see Fig. 9). Fixed to the 30 shaft 13 is a worm 14 meshing with a worm wheel 15 rotatably mounted on a transverse shaft 16 suitably journaled within a base frame 17 suitably secured to the truck frame. This worm wheel 15 may be operatively connected to the 35 shaft 16 by means of a multiple disc clutch 18 of a usual design having suitable cam operating mechanism including a hand lever 19. Fixed to this transverse shaft 18 is a brake drum 20 which is engaged by a brake band 21 also arranged to 40 be controlled by the hand lever 19. When this hand lever is swung in one direction the clutch 18 is applied and the brake 21 released and in the opposite direction the brake is applied and the clutch released, although it is obvious that 45 separate operating means may be employed for the clutch and brake if desired. Journaled on the shaft 16 is a spur gear 22 connectible with the shaft by a jaw clutch 23 splined to the shaft and this gear meshes with a spur gear 24. The 50 spur gear 24 is connected to a transverse shaft 25 suitably journaled within the base frame 17. Keyed to the shaft 16 is a spur pinion 26 meshing with a spur gear 27 secured to a transverse shaft 28 arranged parallel with the shaft 16. 55 Splined to the shaft 28 is a slideable pinion 29 adapted to mesh with a spur gear 30 keyed to a sleeve 31 herein formed integral with the spur gear 22. If desired, operating mechanism may be provided for the clutch 23 and the sliding pinion 29 so that when one is connected the 60 other is released. As illustrated, secured to the shaft 25 is a chain sprocket 32 connected by an endless chain connection 33 to a chain sprocket 65 secured to the rear truck axle. The front and rear truck axles are connected together by a chain and sprocket connection 34. From the foregoing description it will be evident that when the jaw clutch 23 is shifted to connect the spur gear 22 to the shaft 16 and the pinion 29 is out of mesh 70 with the gear 30 the truck wheels may be driven at a relatively high speed from the motor 10 through worm gearing 14, 15, friction clutch 18, shaft 16, spur gearing 22, 24 and the chain and sprocket connections 32, 33 and 34. It will also 75 be evident that when the jaw clutch 23 is in its

released position and the spur pinion 29 is slid into meshing engagement with the gear 30, the truck wheels may be driven at a relatively slow speed appropriate for cutting through the reduction gearing 26, 27, 29 and 30. Upon reversal of the motor 10 the truck wheels may be driven to 5 propel the apparatus in a reverse direction at either a relatively high or a relatively low speed.

Now referring to the turntable mounting for the cutting mechanism, it will be noted that 10 supported for vertical adjustment relative to the truck frame is a supporting frame in the form of an annulus or ring 35 adapted to support the kerf cutting mechanism as will hereinafter appear. To this ring are attached a plurality of, 15 herein three, depending brackets 36, the lower ends of which are shaped to engage respectively with upstanding guide members 37 which are secured to the truck frame and which serve to prevent lateral movement of the ring and attached parts relative to the truck frame. Secured to these depending brackets 36 are screw nuts 38 (see Fig. 7) which are threadedly engaged with vertical screws 39 supported at their upper ends by the upstanding guide members 37 and 20 at their lower ends in step bearings 40 formed in bearing brackets 41 attached to the bottom of the truck frame. It will be noted that the screw nuts are so connected to the feet of the depending brackets as to permit a slight relative rocking movement between the parts. The three sets of screws and guide members constitute upright supports for the annular supporting frame or ring 35 and the latter can be adjusted vertically in parallelism or angularly by suitable rotation of the screws. Rotatably mounted upon each of the screws 39 at its lower end is a chain sprocket 42 and these sprockets are driven by an endless chain 43. Idler sprockets 44 and 45 serve to guide the chain 43 relative to the chain 40 sprockets 42, the sprocket 45 being adjustable to 35 vary the tension of the chain 43. As shown in Fig. 7, the chain sprockets 42 have formed thereon clutch teeth 46 adapted to engage with similar teeth on clutch members 47 splined to the 45 lower ends of the screws. The screws extend downwardly through openings in the top plate 48 of the truck frame. The clutch members 47 are each provided with a groove 49 in engagement with an arm 50 attached to a vertical operating 50 shaft 51. The shafts 51 extend through the top plate 48 of the truck and are each provided with a conveniently located handle 52 by which the movement of the clutch member 47 may be controlled. It will thus be seen that when all the 55 clutches 47 are in a position to connect the chain sprockets to the screws the latter may be simultaneously rotated to move the turntable 4 together with the cutting mechanism supported thereby into different elevated positions relative 60 to the truck frame. It will also be noted that by releasing certain of these clutches and connecting certain others the screws may be so rotated as to effect tilting movement of the turntable about a horizontal axis. The mechanism for 65 driving the screws 39 from the motor 10 herein comprises a bevel pinion 53 (see Fig. 9) journaled on the shaft 16 and connectible to the shaft by the jaw clutch 23. This bevel pinion meshes with a bevel gear 54 fixed to a vertical shaft 55 suitably journaled within the base frame 17. Keyed to the lower end of the shaft 53 is a chain sprocket 56 which engages and drives the endless chain 43.

The turntable 4 supported by the annular sup- 75

porting frame or ring 35 is in the form of a circular casting which constitutes the main base frame of the cutting mechanism. This casting forms the turntable rotatable about the center 5 of the ring 35 and is guided for rotative movement in the ring by a depending annular flange 57 fitting the interior periphery of the ring and by a radial flange 58 overlying the top surface of the ring. If desired, suitable anti-friction 10 rollers of any conventional design may be provided between the turntable and the annular supporting frame 35 for reducing the friction between the turntable and ring. In the outer edge of the turntable casing is formed a series of 15 notches 59, and cooperating with these notches is a slideable locking plate 60 mounted in a guideway formed within a bracket 61 secured to the annular supporting frame 35. This locking member when in its inner position is adapted to 20 engage certain of the notches 59 to lock the turntable against rotation relative to the annular supporting frame 35. Motor operated devices are employed for rotating the turntable relative to the annular supporting frame and herein comprises a motor 65, herein preferably of the reversible electric type, suspended beneath the turntable and having its armature shaft 66 horizontally disposed and extending transversely across the turntable. Fixed to the armature shaft is a 25 bevel pinion 67 meshing with a bevel gear 68 keyed to a vertical shaft 69 suitably journaled within the turntable casting. Fixed to the shaft 69 is a spur gear 70 and meshing as shown in Fig. 3 with spur gears 71 and 72. Rotatable with the spur gear 71 is a worm 73 meshing with a 30 slow speed worm wheel 74. This worm wheel is connectible by a usual multiple disc clutch 75 having any suitable type of operating means, to a transverse shaft 76 likewise suitably journaled within the turntable casting. Fixed to this shaft 35 is a worm 77 meshing with a worm wheel 78 keyed to a vertical shaft 79 suitably journaled within the turntable casting. Fixed to the lower end of this shaft is a spur pinion 80 meshing with internal gear teeth 81 herein cut in the inner wall of the annular supporting frame 35 for the turntable. Rotatable with the spur gear 72 is a worm 83 meshing with a fast speed worm wheel 84 having its teeth oppositely inclined from 40 the teeth of the worm wheel 74 and operative upon application of a multiple disc clutch 85 to effect drive of the shaft 76 at a fast speed in a direction opposite from the slow speed drive. It will thus be seen that upon application of one or the other of the clutches 75, 85 the turntable 45 may be rotated relative to the annular supporting frame 35 at a relatively high speed in one direction or at a relatively low speed appropriate for cutting in the opposite direction.

Now referring to the cutting mechanism supported by the turntable 4, it will be observed that the turntable casting is provided with an integral box-like extension or arm 86 rigidly braced with respect to the turntable by horizontal webs 87 and overlying the ring 35 and the forward end of the truck. Formed integral with this extension or arm at its outer end is a circular flange 88 arranged in a substantially vertical position and rigidly braced with respect to the arm by 50 means of vertical webs 89. As shown in Fig. 4 secured to this circular flange 88 is an annular retaining and bearing sleeve 90 having an inwardly directed flange 91. Between the flange 91 and a shoulder 92 formed on the circular flange 88 there is rotatably mounted a sleeve 93

which herein forms a rotatable neck for the cutter head 6 as hereinafter described. This sleeve 93 is fastened to a projecting neck member 94 by which the cutter head 6 is supported. The member 94 also has herein formed integral therewith a pair of parallel portions 95 to which guideways hereinafter described are secured, these members being connected adjacent their lower ends by a transverse web 96 and being connected by webs 97 to the neck member 94, while curved webs 98 serve to connect them with a generally circular frame member or housing 99 which will be more fully described. To the members 95 there are secured parallel guideways 100 extending perpendicularly to the neck axis and in which there are slideable cross-head or guide members 101, these being secured to members 102 which are fastened to a cutter supporting frame 103. It will be observed that the frame 103 has secured thereto an annulus 104 which, together with an annular shoulder 105 upon the frame 103, provides an annular guideway for a rotatable frame member 106. Secured to this frame member 106 is a frame 107 which carries the cutter bar 7. The mechanism for effecting rotation of the cutter head 6 about the neck axis herein comprises a beveled gear 108 fixed to the vertical shaft 69 (see Fig. 4). Meshing with this bevel gear is a bevel gear 109 fixed to the rear end of a horizontal longitudinally extending transmission shaft 110 suitably journaled within the turntable casting. Keyed to this shaft is a spur pinion 111 meshing with a spur gear 112 fixed to a parallel shaft 113 likewise suitably journaled within the turntable casting. Formed integral with this shaft 113 is a bevel pinion 114 meshing with reverse bevels 115, 116 (see also Fig. 6). These reverse bevels are alternatively connectible by multiple disc clutches 117 and 118 respectively of a usual design to a transverse shaft 40 119 suitably journaled within the turntable casting. These clutches are provided with any suitable operating means including an operating handle 120 conveniently located at the top of the turntable. Secured to the shaft 119 is a worm 45 121 meshing with a worm wheel 122. As shown in Fig. 3 this worm wheel is keyed to a horizontal longitudinally extending shaft 123 arranged parallel with and at one side of the shaft 110. Fixed to the forward end of the shaft 123 is a spur pinion 124 meshing with an internal gear 125 herein formed integral with the sleeve 93. It will thus be seen that upon suitable application of the clutches 117, 118 the cutter head 6 may be rotated about the neck axis in one direction or the other to position the cutter bar 7 into a plurality of intersecting planes. The worm gears 121, 122 have self-locking teeth and when the clutches 117, 118 are released automatically lock the cutter head 6 against rotation about its axis thereby 50 maintaining the cutter bar in its different adjusted positions about the head axis.

The driving mechanism for the cutting mechanism, and the mechanism for adjusting the cutter bar 7 into parallel planes toward and from the neck axis will now be described. Referring to Fig. 4 it will be observed that keyed to the forward end of the shaft 110 is a spur pinion 130 meshing with a spur gear 131 keyed to a longitudinally extending shaft 132 alined with the neck 70 axis and suitably journaled within the circular flange 88 and the cutter head frame. As shown in Fig. 5, keyed to the forward end of the shaft 132 is a bevel pinion 133 meshing with a large bevel gear 134 enclosed within the frame or housing 99. 75

This bevel gear is connected in non-rotative relation to a sleeve-like nut element 135. Coaxial with the nut element 135 is a splined sleeve 136 which, at its upper end, is keyed to a sleeve member 137. This sleeve member is alternatively connectible by a sliding clutch device 138 to a relatively stationary member 139 secured to the frame 99 or to the nut member 135. Suitable clutch operating mechanism including a pivoted shipper yoke 140 is secured to an operating shaft 141. Also secured to this shaft externally of the cutter head frame is an operating lever 142 (see Fig. 1). Threadedly engaging the nut 135 is a screw shaft 143 having splineways 114 therein cooperating with splines 145 upon the member 136. This screw shaft 143 has a collar 146 thereon engaging a suitable combined bearing and supporting means 147 for the housing or frame 103 and the mechanism supported thereby so that the screw shaft 143 is adapted to effect adjustment of the cutter bar supporting frame 107 along guideways 100 toward and from the neck axis. It will thus be seen that when the clutch device 138 is moved into a position to connect the sleeve 136 to the stationary member 139, the screw shaft 143, due to its splined connection with the sleeve 136, is held against rotation and that upon rotation of the nut member 135 the screw shaft is moved axially to effect adjustment of the cutter bar 1 toward or from the neck axis, depending upon the direction of motor rotation. It will also be noted that when the clutch device 138 is shifted into its opposite position, connecting the sleeve 136 to the bevel gear 134, the sleeve 136 and screw shaft 143 may be rotated together at the same angular speed with no axial adjustment of the shaft, and at that time the screw shaft acts only as a transmission shaft. Journaled on the lower end of the screw shaft is a cutter chain drive sprocket 148 which engages and drives an endless cutter bit carrying cutter chain 149 mounted on the margin of the cutter bar 1. The screw shaft 143 drives the cutter chain and the cutter chain drive sprocket 148 is connectible to the shaft by means of a sliding clutch device 150 having any suitable operating means including a pivoted shipper yoke 151 connected through a crank 152 to an operating shaft 153. Secured to this operating shaft externally of the frame 103 is an operating lever 154 (see Fig. 8).

Mechanism is also employed for effecting swinging movement of the cutter bar 1 relative to the frame 103 and herein comprises a spur gear 155 (see Fig. 5) secured for rotation with the shaft 143 and meshing as shown in Fig. 8 with spur gears 156 and 157. Rotatable with the spur gear 156 is a worm 158 meshing with a slow speed worm wheel 159. This worm wheel is connectible by a usual multiple disc clutch 160 to a transverse shaft 161 having fixed thereto a worm 162 meshing with a worm wheel 163 suitably journaled within the frame 103. This worm wheel, as shown in Fig. 5, is keyed to a shaft 164 having secured thereto a spur pinion 165 meshing with an internal gear 166 formed on the annular supporting member 106 for the cutter bar. Rotatable with the spur gear 157 is a worm 167 meshing with a fast speed worm wheel 168 having its teeth inclined oppositely from the teeth of the worm wheel 159 and operative upon application of a multiple disc clutch 169 to drive the shaft 161 at a fast speed in a direction opposite from the slow speed drive described above. It will thus be seen that upon application of one or the other of the clutches 160, 169 the cutter

bar 1 may be swung about a pivotal axis coincident with the axis of the screw shaft 143 at a relatively high bar positioning speed in one direction or at a relatively slow speed appropriate for cutting in the opposite direction. The worm 5 gearing is of the self-locking type and therefore, when disconnected from the motor, automatically maintains the cutter bar in its different angular positions of adjustment.

Electrical energy may be conducted to the electrical controlling apparatus for the motors 10 and 65 through a usual flexible conductor cable 170 wound upon a cable reel 171 supported on the truck. This cable reel is driven by the motor 10 through the following connections: As mentioned above, journaled on the shaft 16 is a sleeve 31 integral with the spur gear 22 (see Fig. 9) and rotatable therewith at either a fast or a slow speed. Splined to this sleeve is a suitable jaw clutch 172 having clutch teeth engageable with 20 clutch teeth 173 formed upon a driving pulley 174 journaled on the sleeve 31. This pulley 174 is connected by a belt 175 to a pulley 176 secured to the cable reel. It will be evident that as the truck wheels are driven to propel the apparatus 25 in either direction along the mine trackway, the cable reel may be also rotated to wind in or pay out the conductor cable.

The preferred mode of operation of the improved mining apparatus will now be described: 30 The apparatus is propelled about the mine forwardly along the mine trackway at a relatively fast transport speed through the truck driving gearing 14, 15, 22, 24 driven by the motor 10. When the apparatus is traveling about the mine 35 the turntable 4, cutter head 6, and cutter bar 1 are disposed in their transport position with the cutter bar above the level of the trackway as shown in Fig. 2. When the working face is reached the fast truck wheel drive is disconnected 40 from the motor 10 by releasing the friction clutch 18 and the jaw clutch 23. If it is desired to make a swinging cut at or near the level of the mine bottom in front of the end of the trackway, the operator first applies the friction clutch 169 controlling the fast speed bar swinging mechanism and the cutter bar 1 is swung about its pivot 45 relative to the cutter head at a relatively fast bar positioning speed from the position shown in Fig. 1 laterally to a position adjacent the right hand rib of the entry, the friction clutch 169 thereafter being released. The operator then shifts the clutch device 138 to a position to connect the sleeve 136 to the relatively stationary member 139 and upon starting of the motor 65 50 the cutter bar may be moved rectilinearly along the guideways 100 downwardly away from the head axis until it occupies a position at or near the level of the mine bottom as shown in Fig. 11; the adjusting mechanism being driven from the motor 65 through bevel gearing 67, 68, 108, 109, shaft 110, spur gearing 139, 131, shaft 132 and bevel gearing 133, 134. The clutch device 138 is then shifted downwardly to disconnect the sleeve 136 from the relatively stationary member 139 55 and to connect the sleeve to the gear 134 and the clutch device 150 moved to a position to connect the cutter chain drive sprocket 148 to the shaft 143, and as a result, the cutter chain 149 is rapidly circulated about the margin of the cutter 60 bar 1, the screw shaft 143 then acting only as a transmission shaft with no axial adjustment. The friction clutch 169 controlling the slow speed bar swinging mechanism is then applied and the cutter bar 1 is swung transversely in its plane 70 65 75

across the front end of the trackway to make an arcuate cut beneath the coal. When the cutter bar reaches a position adjacent the left hand rib, the friction clutch 160 is released. After the completion of the swinging cut, the cutter chain 149 is disconnected from its drive, the clutch device 138 shifted to connect the sleeve 136 to the relatively stationary member 139 and upon reversal of the motor 65 the cutter bar is moved upwardly rectilinearly along the guideways 100 toward the neck axis to the position shown in Fig. 2, the clutch device 138 thereafter being moved to its neutral position. The motor 10 is then reversed, the clutches 18 and 23 connected and the apparatus is then propelled rearwardly at a high speed along the mine trackway to the mine entry. If it is desired to cut a horizontal kerf at or near the level of the mine bottom outside of and below the level of the mine trackway, the operator slides the locking member 60 for the turntable into its released position, starts the motor 65 in the proper direction, and upon application of the clutch 85, the turntable 4, together with the cutting mechanism supported thereby, is swung horizontally from the position shown in Fig. 1 to the full line position indicated at A in Fig. 12. During horizontal swinging movement of the turntable relative to the truck the cutter bar 7 may be swung simultaneously about its pivot relative to the cutter head in the opposite direction under the control of the slow speed bar swing clutch 160 until the parts assume the position shown. When the parts are thus disposed with the bar pivot lying outside of the mine trackway, the operator releases the friction clutches 85 and 160 and then locks the turntable by sliding the locking member 60 into one of the notches 59 on the turntable. The clutch device 138 is then shifted to a position to connect the sleeve 136 to the relatively stationary member 139 and upon actuation of the driving gearing 133, 134, the cutter bar is moved rectilinearly downwardly along the guideways 100 away from the head axis until it occupies a position at or near the level of the mine bottom, the cutter bar being positioned relative to the mine bottom as shown in Fig. 11 at that time. The clutch device 138 is then moved to connect the sleeve 136 and the nut 135 and the clutch device 150 connected, thereby effecting circulation of the cutter chain about the margin of the cutter bar 7. The motor 10 is then started in the proper direction and the apparatus propelled forward bodily along the mine trackway at a relatively slow cutting speed, sumping the cutter bar beneath the coal from position A shown in Fig. 13 to position B indicated in dotted lines in that figure. The friction clutch 18 is then released and the brake 21 set. The operator then releases the locking member 60 for the turntable and upon application of friction clutch 75 the turntable 4, together with the cutting mechanism supported thereby, is swung horizontally at a low cutting speed to effect horizontal swinging movement of the cutter bar in its plane. During the initial swinging movement of the turntable the cutter bar 7 is swung about its pivot in a reverse direction under the control of the friction clutch 169 until the parts assume a straight line position wherein the cutter bar 7 extends parallel to a line including the bar pivot and the turntable axis as indicated at C in Fig. 12. After the cutter bar has reached the left hand rib as indicated at D in Fig. 12 and the swinging cut has been completed, the cutter bar 7 is again swung about its pivot rearwardly under the con-

trol of the friction clutch 169, while rotation of the turntable 4 is continued, the turntable and cutter bar swinging simultaneously in opposite directions at that time until they assume the position indicated at E in Fig. 12. The turntable 4 is then locked against rotation and the brake 21 released, and upon reversal of the motor 10 and application of the friction clutch 18 the apparatus is propelled bodily rearwardly along the mine trackway at a slow cutting speed, moving the cutter bar from the position E in Fig. 12 to position F in that figure. As a result, it will be evident that a horizontal plane kerf may be cut at or near the level of the mine bottom in accordance with the arcwax method of cutting. After the completion of the cut beneath the coal the parts are again returned to their transport position shown in Fig. 2. A horizontal kerf may be cut at or near the level of the mine roof by connecting the elevating screws 39 to the motor 10, thereby elevating the turntable 4, together with the cutting mechanism supported thereby bodily relative to the truck to the position shown in Fig. 13. The cutter head 6 is then rotated about the neck axis to a position wherein the cutter bar 7 occupies its top cutting position. The cutter bar is then adjusted vertically rectilinearly along the guideways 100 away from the head axis until the same assumes a position as indicated in Fig. 13. The cutter bar is then sumped in, swung transversely in its plane and withdrawn from the coal in accordance with the usual arcwax method of cutting. It will herein be noted that during any of the horizontal cutting operations described above, for instance when it is desired to cut on a rolling bottom, the cutting mechanism may be tilted about a transverse axis simply by disconnecting certain of the elevating screws 39 from the motor while others are rotated, thereby causing the turntable to be tilted relative to the horizontal. For instance, if it is desired to tilt the tip end of the cutter bar downwardly, this may be accomplished by disconnecting the clutches for the front elevating screws 39 while the rear elevating screw is connected to the motor 10, thereby causing the rear edge of the turntable to be elevated. Conversely, if it is desired to tilt the tip end of the cutter bar upwardly, the rear elevating screw may be disconnected from the motor while the front elevating screws are rotated, thereby causing the forward edge of the turntable to be tilted upwardly. It will also be noted that upon certain adjustment of the elevating screws, the turntable may be tilted into different angular positions about transverse or longitudinal axes or any intermediate axes desired, thereby enabling the cutter bar to be positioned to suit different mining conditions. A shear or vertical cut may be inserted in the coal face simply by applying one or the other of the reverse frictions 117, 118 controlling the reverse bevels 115, 116 respectively thereby enabling the cutter head 6 to be rotated about the neck axis by the motor 65 through the gearing 67, 69, 108, 109, shaft 110, gearing 111, 112, the bevel pinion 114, one or the other of the reverse bevels 115, 116, worm gearing 121, 122, shaft 123, and pinion 124 meshing with the internal gear 125 secured to the cutter head to bring the cutter bar 7 into a position to swing vertically as shown in Fig. 14. During the shearing operation the cutter bar is first sumped in, then swung downwardly in its plane and thereafter withdrawn from the coal in a manner similar to

- that described above in regard to horizontal cutting in accordance with the arcweld method. It will further be noted that the cutter bar may be moved bodily toward and from the neck axis into 5 different parallel planes in any of its positions about the neck axis, thereby enabling the apparatus to cut parallel horizontal kerfs and parallel vertical kerfs and kerfs in a plurality of intersecting planes.
- 10 As a result of this invention, it will be noted that an improved coal mining apparatus is provided which is adapted to cut horizontally at or near the level of the mine bottom outside the mine trackway and below the track rails and also 15 to make shear or vertical cuts, thereby facilitating the shooting of the coal from the solid and increasing the quantity of lump coal obtainable. It will further be noted that under certain conditions, the cutter bar may be adjusted to cut at 20 or near the level of the mine roof; or if desired in parallel planes between the mine roof and mine bottom. It will still further be noted that an improved "universal" coal cutter is provided having improved adjustable kerf cutting mechanism 25 whereby the cutter bar may be positioned to cut in parallel planes either vertically or horizontally within a comparatively wide cutting range. It will further be noted that an improved coal cutter is provided wherein the adjusting mechanism for the kerf cutting mechanism is extremely flexible, it being possible to operate the apparatus as a mounted bottom cutter, top cutter, shear cutter and slabbing machine, thereby enabling the apparatus to accommodate itself 30 to practically every mining condition encountered wherever the use of mounted track cutters is possible. These and other uses and advantages of the improved mining apparatus will be clearly apparent to those skilled in the art.
- 35 40 While there is in this application specifically described one form which the invention may assume in practice, it will be understood that this form of the same is shown for purposes of illustration and that the invention may be modified and embodied in various other forms without departing from its spirit or the scope of the appended claims.
- 45 What I claim as new and desire to secure by Letters Patent is:
- 50 1. In a mining apparatus, a wheeled truck 55 adapted to run along a trackway, a horizontal turntable mounted thereon for rotation about a vertical axis, an annular supporting frame for said turntable, a frame on said turntable having an arm overlying said annular frame and projecting outwardly beyond said annular frame and a drop support mounted on said projecting arm and having a depending neck extending downwardly below the annular frame, kerf cutting 60 mechanism mounted on said turntable including a cutter carrying head mounted on said depending neck for rotation about a horizontal axis disposed below the top surface of said annular frame and extending radially from said turntable axis 65 and a cutter bar pivotally mounted on said cutter head, a motor carried by said turntable, mechanism driven by said motor for driving said cutting mechanism, mechanism driven by said motor for rotating said turntable relative to said annular supporting frame, mechanism driven by said motor for rotating said cutter head about its axis relative to said turntable, mechanism driven by said motor for swinging said cutter bar about its pivot relative to said cutter head while said turntable remains stationary, and motor operated de-

vices for adjusting said annular supporting frame vertically relative to said truck.

2. In a mining apparatus, a wheeled truck 5 adapted to run along a trackway, a horizontal turntable mounted on said truck for adjustment vertically in parallelism relative thereto and for tilting movement relative to said truck about a horizontal axis, an annular supporting frame for said turntable, kerf cutting mechanism mounted on said turntable including a cutter bar swingable with said turntable to cut a horizontal kerf, a motor carried by said turntable, a direct intermeshing gear drive between said motor and said annular supporting frame for rotating said turntable about its axis to effect swinging movement 10 of said cutter bar and including an internal gear on the inner periphery of said annular frame and a gear on said turntable meshing with said internal gear, mechanism driven by said motor for driving said cutting mechanism, and motor operated devices on said truck for adjusting said annular supporting frame vertically relative to said truck and for tilting said frame about a horizontal axis.

3. In a mining apparatus, a wheeled truck 25 adapted to run along a trackway, a horizontal turntable thereon rotatable relative thereto about a vertical axis, motor operated devices for adjusting said turntable bodily into different elevated positions relative to said truck and for tilting said turntable about a transverse horizontal axis relative to said truck, kerf cutting mechanism carried by said turntable, a motor carried by said turntable, and mechanism including a direct intermeshing gear drive connected to said turntable 30 and driven by said motor for rotating said turntable about its axis relative to said truck, said rotating mechanism including a relatively stationary internal gear arranged adjacent the outer periphery of said turntable and relative to which said turntable is rotatable and a gear on the turntable meshing with said internal gear.

4. In a mining apparatus, a wheeled truck 45 adapted to run along a trackway, a horizontal turntable thereon rotatable relative thereto about a vertical axis, motor operated devices for adjusting said turntable bodily into different elevated positions relative to said truck and for tilting said turntable about a transverse horizontal axis relative to said truck, kerf cutting mechanism carried by said turntable, a motor carried by said turntable, and mechanism including a direct intermeshing gear drive connected to said turntable 50 and driven by said motor for rotating said turntable about its axis relative to said truck, said intermeshing gear drive including a relatively stationary internal gear arranged adjacent the outer periphery of said turntable and relative to which said turntable is rotatable, and a gear on the turntable meshing with said internal gear and a manually controllable reversing device operable at will to effect rotation of said turntable gear to effect rotation of said turntable 55 in either of opposite directions without reversing said motor.

5. In a mining apparatus, a wheeled truck 60 adapted to run along a trackway, a support mounted thereon for vertical adjustment relative thereto, a horizontal turntable carried by said support and rotatable relative thereto about a vertical axis, said turntable being tiltable relative to said truck into different angular positions relative to the horizontal, a drop frame supported on said turntable and extending downwardly below the top of the turntable and support in advance 65

of said truck, a support mounted on said drop frame for rotation about a longitudinal axis disposed below the top surface of said turntable support, a frame mounted on said second support for adjustment toward and from the axis of said second support, and a cutter bar carried by said adjustable frame and swingable relative thereto.

6. In a mining apparatus, kerf cutting mechanism including a swingable kerf cutter, a motor mounted to swing with said kerf cutter, and means driven by said motor for actuating the cutting elements of the kerf cutter including a vertical driving shaft, and mechanism for swinging said kerf cutter at a high positioning speed in one direction and at a relatively low cutting speed in the opposite direction including a fast speed gear train and a slow speed gear train, each gear train including intermeshing transmission gears and means for driving said gear trains from said 20 driving shaft.

7. In a mining apparatus, a wheeled truck adapted to run along a mine trackway, a horizontal turntable on said truck, devices for adjusting said turntable into different elevated positions relative to said truck, an arm fixed to the turntable and projecting horizontally therefrom, a cutter head mounted on the outer extremity of said arm for rotation about a horizontal axis disposed below the top surface of the turntable 30 and extending radially from the axial line of the turntable, a kerf cutter pivotally mounted on said cutter head for swinging movement relative thereto about an axis perpendicular to the axial line of the cutter head, means operable to turn said turntable, means operable to rotate said cutter head, and means operable to swing the kerf cutter about its pivot.

8. In a mining apparatus, a wheeled truck adapted to run along a mine trackway, a horizontal widely extended circular turntable mounted on said truck for rotation about a normally vertical axis, an annular frame extending completely around the outer periphery of said turntable and supporting the latter, an arm fixed to said turntable and projecting horizontally therefrom beyond the outer edge of said annular supporting frame and having a depending portion at its outer extremity extending downwardly below the bottom of said annular supporting frame, a support mounted on said depending portion of said arm for rotation about an axis extending radially from the axial line of the turntable and having depending guideways, a frame mounted on said support for adjustment along said guideways toward and from the axial line of said support, a kerf cutter pivotally mounted on said adjustable frame for swinging movement relative thereto about an axis perpendicular to the axial line of said support, means operable to rotate said support about its axis, means operable to adjust said frame toward and from the axis of said support, and means operable to swing said kerf cutter about its pivot.

9. In a mining apparatus, a wheeled truck adapted to run along a trackway, a horizontal turntable thereon, motor operated devices for bodily adjusting said turntable into different elevated positions relative to said truck and for tilting said turntable about a transverse axis relative to said truck, a drop support on said turntable including a horizontal frame portion projecting outwardly from said turntable in advance of the forward edge of the turntable and a depending neck frame on the outer extremity 70 of said horizontal frame portion and extend-

ing downwardly in advance of the forward end of the truck, kerf cutting mechanism mounted on said turntable including a cutter head mounted on said depending neck frame for rotation about a longitudinal axis disposed below the top surface of said turntable and a cutter bar pivotally mounted on said head for swinging movement relative thereto, and motor operated devices for rotating said cutter head about its axis relative to said turntable and for swinging said cutter bar about its pivot relative to said cutter head while said turntable remains stationary, the mechanism for rotating said cutter head about its axis including gearing including a gear element fixed to said cutter head and rotatable therewith on said longitudinal axis and a gear element meshing with said first mentioned gear element and rotating on an axis fixed as to movement relative to said longitudinal axis.

10. In a machine of the class described, a movable base, a support mounted on said base for swinging movement relative thereto about a normally vertical axis and also for universal tilting movement relative thereto, a supporting frame for said support and on which said support is 20 rotatably mounted, said frame being tiltable with said support, a substantially horizontally extending cutter bar, mounting means for the cutter bar in connection with the support whereby the bar is movable relative to the support about a 25 plurality of rectangularly related axes of which one is substantially on the horizontal and disposed outside and below the top surface of said support supporting frame, means operable to tilt the support, means operable to swing the support, and means operable to move the cutter bar about said plurality of axes including a pair of gear elements one rotatable on each of said axes and each rotating during movement of the bar about its respective axis at the same angular 30 rate as the cutter bar.

11. In a machine of the class described, a truck adapted to travel over a mine track, a turntable, means supporting said turntable on said truck for rotation relative to the truck on a normally 45 vertical axis and also for universal tilting movement relative to the truck, an arm fixed to the turntable and projecting horizontally therefrom and a depending neck carried by said arm and extending downwardly below the top of said turntable supporting means in advance of the latter and said truck, a kerf cutter supported by said depending neck for movement relative thereto about a plurality of rectangularly related axes of which one is substantially on the horizontal, the 50 horizontal axis being disposed below the top surface of said turntable supporting means, means operable to tilt the turntable, means operable to swing the turntable, and means operable to move the cutter bar about said plurality of axes including a pair of gear elements one rotatable on each of said axes and each rotating during movement of the bar about its respective axis at the same 55 angular rate as the cutter bar.

12. In a machine of the class described, a truck 65 adapted to travel over a mine track, a turntable, means supporting said turntable on said truck for rotation relative to the truck on a normally vertical axis and also for universal tilting movement relative to the truck, an arm fixed to the 70 turntable and projecting horizontally therefrom, a rotatable shaft extending longitudinally of said arm in a horizontal plane below the top of the turntable, a head mounted on said arm and rotatable about an axis in the same straight line 75

- with the axis of said shaft, a shaft journaled in said head at right angles to the first mentioned shaft, a cutter bar supported by said head for swinging movement about the second-named shaft, a cutter chain drive sprocket on said second-named shaft to be driven thereby, a motor on said turntable, means driven by the motor to swing the turntable, to drive the sprocket shaft, to rotate said head relative to said arm, and to swing the cutter bar relative to the head, and means operable to tilt the turntable.
13. In a mining apparatus, a wheeled truck adapted to run along a trackway, a horizontal turntable mounted on said truck for rotation about a vertical axis, an annular supporting frame for said turntable, a frame on said turntable having an arm overlying said annular frame and projecting outwardly beyond said annular frame and a drop support mounted on the outer extremity of said projecting arm and having a depending portion extending downwardly below the annular frame, kerf cutting mechanism carried by said turntable including a cutter bar pivotally supported on the depending portion of said drop support to swing in horizontal planes about an axis parallel to said turntable axis, said turntable, drop support and cutting mechanism being adjustable relative to said truck to position said cutter bar to cut a horizontal kerf at the level of the mine bottom outside and below the level of the trackway and in advance of the trackway, a motor carried by said turntable, mechanism driven by said motor for rotating said turntable relative to said annular supporting frame, mechanism driven by said motor for swinging said cutter bar about its pivot while said turntable remains stationary, and motor operated devices for adjusting said annular supporting frame vertically relative to said truck.
14. In a mining apparatus, a wheeled truck adapted to run along a trackway, a horizontal turntable mounted thereon for rotation about a vertical axis, an annular supporting frame for said turntable, a frame on said turntable having an arm overlying said annular frame and projecting outwardly beyond said annular frame and a drop support mounted on said projecting arm and having at its outer extremity a depending neck portion extending downwardly below the annular frame, kerf cutting mechanism mounted on said turntable including a cutter carrying head mounted on the depending neck portion of said drop support for rotation about a horizontal axis disposed below the top surface of said annular frame and extending radially from said turntable axis and a cutter bar pivotally mounted on said cutter head, said turntable, drop support and cutter head being adjustable relative to the truck to position said cutter bar to cut a horizontal kerf at the level of the mine bottom outside and below the level of the trackway and in advance of the trackway, a motor carried by said turntable, mechanism driven by said motor for driving said cutting mechanism, mechanism driven by said motor for rotating said turntable relative to said annular supporting frame, mechanism driven by said motor for rotating said cutter head about its axis relative to said turntable, mechanism driven by said motor for swinging said cutter bar about its pivot relative to said cutter head while said turntable remains stationary, and motor operated devices for adjusting said annular supporting frame vertically relative to said truck.
15. In a machine of the class described, a movable base, a support mounted on said base for swinging movement relative thereto about a normally vertical axis and also for universal tilting movement relative thereto, a substantially horizontally extending cutter bar, mounting means for the cutter bar in connection with the support whereby the bar is movable relative to the support about a plurality of rectangularly related axes of which one is substantially on the horizontal, the horizontal axis being disposed below the top surface of said rotatable and tiltable support, means operable to tilt the support, means operable to swing the support, and means operable to move the cutter bar about said plurality of axes.
16. In a machine of the class described, a truck adapted to travel over a mine track, a turntable, means supporting said turntable on said truck for rotation relative to the truck on a normally vertical axis and also for universal tilting movement relative to the truck, an arm fixed to the turntable and projecting horizontally therefrom and having a depending neck, a rotatable shaft extending longitudinally of said arm, a shaft parallel with said shaft and disposed below the top surface of the turntable, a head mounted on said depending neck and rotatable about a line including the axis of said parallel shaft as an axis, a third shaft journaled in said head at right angles to the first mentioned shafts, a cutter bar supported by said head for swinging movement about the third named shaft, a cutter chain drive sprocket on said third named shaft to be driven thereby, a motor on said turntable, means driven by said motor to swing the turntable, to drive the sprocket shaft, to rotate said head relative to said arm and to swing the cutter bar relative to the head, and means operable to tilt the turntable.
17. In a mining apparatus, a wheeled truck adapted to run along a mine trackway, a horizontal turntable on said truck, an arm secured to the turntable and projecting outwardly beyond the forward edge of the turntable and in advance of said truck, said arm having at its outer overhanging extremity a depending neck frame extending downwardly below the bottom surface of the turntable, a cutter head rotatably mounted on said depending neck frame to rotate about a horizontal axis extending radially from the turntable axis and disposed below the top surface of the turntable, a kerf cutter pivotally mounted on said cutter head to swing about an axis at right angles to the head axis, and motor operated devices for actuating the kerf cutter including a horizontal shaft journaled on said arm above the top surface of the turntable, a parallel shaft journaled in said depending neck frame and arranged with its axis coincident with the cutter head axis, intermeshing gears on said shafts, a shaft arranged with its axis coincident with the kerf cutter pivot axis and journaled in said cutter head, and intermeshing bevel gearing on said two last named shafts.
18. In a mining apparatus, a wheeled truck adapted to run along a mine trackway, a horizontal turntable on said truck, an arm secured to the turntable and projecting outwardly beyond the forward edge of the turntable and in advance of said truck, said arm having at its outer overhanging extremity a depending neck portion extending downwardly below the bottom surface of the turntable, a cutter head rotatably mounted on said depending neck portion to rotate about a horizontal axis extending radially from the

- turntable axis and disposed below the top surface of the turntable, a kerf cutter pivotally mounted on said cutter head to swing about an axis at right angles to the head axis, and motor operated devices for actuating the kerf cutter including a vertical shaft journaled on said turntable, a horizontal shaft journaled on said arm above the top surface of the turntable, intermeshing bevel gearing on said shafts, a parallel shaft journaled on said depending neck frame and arranged with its axis coincident with the cutter head axis, intermeshing gears on said two last named shafts, a shaft arranged with its axis coincident with the kerf cutter pivot axis and journaled in said cutter head, and intermeshing bevel gearing on said two last named shafts.
19. In a mining apparatus, a wheeled truck adapted to run along a mine trackway, a horizontal turntable on said truck, an arm secured to the turntable and projecting outwardly beyond the forward edge of the turntable and in advance of said truck, said arm having at its outer overhanging extremity a depending neck frame extending downwardly below the bottom surface of
